US00D630222S

(12) **United States Design Patent**
Lin

(10) **Patent No.:** US D630,222 S
(45) **Date of Patent:** ** Jan. 4, 2011

(54) **ELECTRONIC DEVICE HOLDER**

(75) Inventor: **Chung-Hung Lin**, Tainan County (TW)

(73) Assignee: **Jow Tong Technology Co., Ltd.**, Tainan Hsien (TW)

(**) Term: **14 Years**

(21) Appl. No.: **29/362,208**

(22) Filed: **May 21, 2010**

(51) **LOC (9) Cl.** 08-07

(52) **U.S. Cl.** D14/447

(58) **Field of Classification Search** D14/447, D14/451, 432, 439, 217, 251, 253, 250; D13/107, D13/108; D3/218, 269; 379/454, 455; 361/679.03; 248/917, 918, 919, 920, 921, 922, 923, 924

(57) **CLAIM**

The ornamental design for an electronic device holder, as shown and described.

DESCRIPTION

FIG. 1 is a perspective view of an electronic device holder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a second perspective view of the electronic device holder in an alternate position.
